UNITED STATES PATENT OFFICE

JOHN P. NORTHEY, OF TORONTO, ONTARIO, CANADA

SOUND-PRODUCING DEVICE

Application filed June 16, 1930. Serial No. 461,478.

This invention relates to improvements in sound producing devices such as shown in my prior Patent No. 736,428 in which high pressure air was used to vibrate a hollow piston in a cylinder having orifices which, by the vibration of the piston, are alternately brought into and out of alignment with the orifices of the cylinder, thus controlling the flow of low pressure air to cause a rapid succession of puffs to produce a musical note. As the driving of the piston required air at high pressure, a somewhat expensive air compressing and cooling system has heretofore been necessary to provide and store such air, and the object of the present invention is to so construct the device that air at a materially lower pressure may be employed to actuate the piston giving the same stroke as formerly; or if the same pressure as formerly is used a longer stroke and reduced air consumption in the speaking end of the piston will be obtained.

In the earlier constructions the hollow piston was provided with an enlarged head operating in a separate chamber or cylinder of greater diameter than that of the sound producing cylinder and the control of the driving air was effected solely by ports in the enlarged piston head and its cylinder wall. The air passages were thus of necessity of small cross sectional area relative to their length so that frictional losses in the air were high and lag in transmission so great that high air pressures were essential.

In my co-pending application No. 343,817, I show a construction which enabled me to materially reduce the pressure of the driving air and secure a greater length of stroke than was previously possible. This result was attained by providing supplemental inlet and exhaust ports controlled by the parts of the piston and cylinder of smaller diameter, the supplemental exhaust being through the piston wall into the interior of the hollow piston.

It has been found, by further experiment, that it is possible to re-arrange the port system shown in the said application to permit of a further reduction of the pressure of the driving air and to secure even greater length

of stroke for a given air pressure. This result I attain by means of the constructions hereinafter specifically described but which may be briefly outlined as follows. Provisions are made for combining the outlets of the exhaust systems so that the exhaust may be controlled, as, for example, by connecting it with an exhaust pump. Further, as in the present invention the driving air will or may be at a lower pressure than the sound-producing air, I have provided means for using the pressure of the sound producing air to check the back stroke of the piston and to initiate the forward stroke.

The invention is illustrated in the accompanying drawings in which—

Fig. 1 is a sectional detail of parts of the apparatus showing the piston in the exhaust position;

Fig. 2 a similar view showing the piston in the position in which the driving air is admitted behind it; and

Fig. 3 a detail in elevation of part of the cylinder end.

In the drawings like numerals of reference indicate corresponding parts in the different figures.

1 is the casing in which is mounted a cylinder 2. The wall of this cylinder has a series of sound producing orifices 3 formed therein which will usually be spaced at equal distances apart. Within the cylinder a hollow piston 4 is adapted to reciprocate, this piston being also provided with sound producing orifices 5 adapted to be brought into alignment with the orifices in the cylinder by the reciprocation of the piston.

The piston is provided with an enlarged head 6 adapted to reciprocate in the cylinder enlargement 7. The apertured part of the piston is separated from the remainder of the piston by the diaphragm 8. The open end of the piston communicates with the horn 9, which is suitably secured to the end of the casing.

Within the casing is formed the chamber 10 communicating with the air inlet 11. The sound is produced by the reciprocation of the piston, which causes its sound producing orifices to coincide at regular intervals with

the orifices of the cylinder 2, thus producing a series of puffs of air which occur at such intervals as to form a musical note.

The piston and casing are constructed in the following manner to effect the reciprocation of the piston. The cylinder enlargement 7 is provided with the annular ports 12, 13, which are connected by a plurality of longitudinal passages 25. In the wall of the cylinder enlargement is also formed an annular port 14 with which communicate a plurality of radial passages 15 which communicate with an annular chamber 16 formed in the cylinder enlargement 7. With this chamber communicates the air inlet 17. Intermediate the ports 12 and 13 is an annular exhaust port 18 with which communicate a plurality of radial passages 19 which communicate with an annular chamber 20 formed between the casing and the cylinder enlargement. The piston head has an annular groove 23 formed in its exterior surface, which is so positioned that, when it forms a communication between the exhaust port 18 and the port 13, the port 12 is uncovered. Also through the head of the piston are formed a plurality of passages 24 opening through the forward face of the piston head and through its periphery. Preferably the inner parts of these passages are formed by an annular groove in the exterior surface of the piston head.

Assuming the other ports shown in the drawings are omitted, it follows from the construction described that, when the parts are in the position shown in Fig. 1, air from behind the piston head is exhausted through the port 12, the longitudinal passages 25, the port 13, the groove 23, the exhaust port 18, the passages 19, and the chamber 20. The momentum of the piston then carries it a little further to the right. There is then the condition that air under pressure is acting on the front of the piston while the pressure has been exhausted from behind. The piston is then forced to the position shown in Fig. 2 in which the groove 23 no longer forms a communication between the port 13 and the exhaust port 18. In this position the port 13 is still open to the space behind the piston head while the passages 24 provide a passage for air from the space in front of the piston head through the port 13, passages 25 and port 12 to the space behind the piston head. The same air pressure then exists both in front of and behind the piston head, but, owing to the greater surface of the piston head exposed to air pressure at the back than at the front, the excess pressure drives the piston forward to and beyond the exhaust position previously described. The piston is thus reciprocated to effect sound production as hereinbefore described.

The parts previously described are old in the art, but to them I have now added the

following features of construction to give a supplemental exhaust and air admission for the driving of the piston. In the cylinder wall I form an annular supplemental exhaust port 26 with which communicate a series of radial passages 27 communicating with an annular chamber 33 formed between the casing and the cylinder wall. The annular passages 20 and 33 are connected at one side of the device with a common outlet 34. Formed in the wall of the piston is an annular port 28 which communicates with a series of longitudinal passages 29 formed in the wall of the piston and opening through its rear end. Thus part of the exhaust takes place directly from the passages 25 through the port 18, the radial passages 19 to the annular chamber 20, while another portion passes through the passages 29, the port 28 and the radial passages 27 to the annular chamber 33. The chambers 20 and 33 having a common outlet, any desired control means may be applied to the exhaust, as, for example, by providing means to choke the exhaust and create back pressure, or by applying suction to the outlet to increase the rapidity of the exhaust and thus increase the piston stroke.

A supplemental path for air under pressure is provided through the medium of the supplemental inlet port 30 formed in the cylinder wall and the radial passages 31 formed in the cylinder wall and communicating with the chamber 16. In the piston wall is formed an annular port 36 communicating with the passages 29 and adapted to register with the supplemental inlet port 30 when the port 24 is admitting air to the port 13.

When the driving air pressure is reduced much below that of the sound-producing air, it may be found that the return stroke of the piston is insufficiently cushioned. I therefore provide means for using the high pressure air to cushion the back stroke and initiate the forward movement of the piston. For this purpose I provide the annular port 32 in the wall of the cylinder communicating with the radial passages 34 which in turn communicate with the longitudinal passages 35 leading to the chamber 10 into which the driving air is introduced. It will be noted that on the return stroke of the piston the port 36 first registers with the port 30 to admit driving air behind the piston and that a continuation of the return movement under the influence of momentum will cause the port 28 to register with the port 32 to admit the sound producing air behind the piston and check its rearward movement. The piston then moves forward to and past the position shown in Fig. 2, in which the ordinary driving air is admitted behind the piston both by the ports of the piston and cylinder, and the ports of the piston and cylinder enlargements, and to the exhaust position shown in Fig. 1. The pressure be-

hind the piston is then exhausted both through the ports of the piston and cylinder and the ports of the piston and cylinder enlargements and the cycle recommences.

5 I find that with the new construction driving air may be employed at a lower pressure even than that of the sound producing air, thus not only effecting economies in operation but also in the expense of installation, or as an alternative a longer stroke may be 10 obtained by using the higher pressures now commonly employed.

What I claim as my invention is:

1. A sound producing device comprising 15 a cylinder having sound producing orifices in its wall; a hollow piston adapted to reciprocate in said cylinder, open at one end and having sound producing orifices in its wall adapted to be brought into alinement with 20 the orifices in the cylinder by the reciprocation of the piston; an enlarged head at the end of the piston remote from its open end; an enlargement of the cylinder in which the piston head reciprocates; an air inlet and an 25 air outlet in said enlargement; ports in the piston head and the wall of the cylinder enlargement controlling the admission and exhaust of the piston driving air; an exhaust port in the cylinder; a passage in the cylinder 30 wall forming a communication between the last mentioned port and an exhaust outlet; a port in the piston wall; and a passage leading from said port through the piston to the back thereof, whereby air is exhausted 35 through the cylinder wall at the end of the forward stroke as well as through the cylinder enlargement.

2. A sound producing device comprising 40 a cylinder having sound producing orifices in its wall; a hollow piston adapted to reciprocate in said cylinder, open at one end and having sound producing orifices in its wall adapted to be brought into alinement with the orifices in the cylinder by the reciprocation 45 of the piston; an enlarged head at the end of the piston remote from its open end; an enlargement of the cylinder in which the piston head reciprocates; ports in the piston head and the wall of the cylinder enlargement 50 controlling the admission and exhaust of the piston driving air; and co-operating ports, and passages in the cylinder and piston walls forming an exhaust supplemental to that of the piston head and cylinder enlargement and discharging independently 55 through the cylinder wall.

3. A sound producing device comprising 60 a cylinder having sound producing orifices in its wall; a hollow piston adapted to reciprocate in said cylinder, open at one end and having sound producing orifices in its wall adapted to be brought into alinement with the orifices in the cylinder by the reciprocation 65 of the piston; an enlarged head at the end of the piston remote from its open end;

an enlargement of the cylinder in which the piston head reciprocates; ports in the piston head and the wall of the cylinder enlargement controlling the admission and exhaust of the piston driving air; co-operating ports 70 and passages in the cylinder and piston walls forming an exhaust supplemental to that of the piston head and cylinder enlargement and discharging independently through the cylinder wall; and a casing formed with a chamber coupling the exhaust outlet of the cylinder enlargement and the supplemental exhaust outlet of the cylinder. 75

4. A sound producing device comprising 80 a cylinder having sound producing orifices in its wall; a hollow piston adapted to reciprocate in said cylinder, open at one end and having sound producing orifices in its wall adapted to be brought into alinement with the orifices in the cylinder by the reciprocation 85 of the piston; an enlarged head at the end of the piston remote from its open end; an enlargement of the cylinder in which the piston head reciprocates; an air inlet and an air outlet in said enlargement; ports in the piston head and the wall of the cylinder enlargement 90 controlling the admission and exhaust of the piston driving air; an inlet port in the cylinder wall; a passage in the cylinder wall forming a communication between the last mentioned port and an inlet of the driving air; a port in the piston wall; and a passage leading from said port through the piston to the back thereof, whereby driving air 95 may be admitted through the piston wall as well as through the cylinder enlargement. 100

5. A sound producing device comprising 105 a cylinder having sound producing orifices in its wall; a hollow piston adapted to reciprocate in said cylinder, open at one end and having sound producing orifices in its wall adapted to be brought into alinement with the orifices in the cylinder by the reciprocation 110 of the piston; an enlarged head at the end of the piston remote from its open end; an enlargement of the cylinder in which the piston head reciprocates; an air inlet and an air outlet in said enlargement; ports in the piston head and the wall of the cylinder enlargement 115 controlling the admission and exhaust of the piston driving air; an inlet port in the cylinder wall; a passage in the cylinder wall forming a communication between the last mentioned port and an inlet of the driving air; a port in the piston wall; a passage leading from said port through the piston to the back thereof, whereby driving air 120 may be admitted through the piston wall as well as through the cylinder enlargement. 125

130

tioned to come into co-operation on the return stroke of the piston after the previously mentioned ports of the piston and cylinder.

6. A sound producing device comprising a cylinder having sound producing orifices in its wall; a hollow piston adapted to reciprocate in said cylinder, open at one end and having sound producing orifices in its wall adapted to be brought into alinement with the orifices in the cylinder by the reciprocation of the piston; a chamber in the device for the sound-producing air supply; an enlarged head at the end of the piston remote from its open end; an enlargement of the cylinder in which the piston head reciprocates; an air inlet and an air outlet in said enlargement; ports in the piston head and the wall of the cylinder enlargement controlling the admission and exhaust of the piston driving air; an inlet port 20 in the cylinder wall; a passage in the cylinder wall forming a communication between the last mentioned port and an inlet of the driving air; a port in the piston wall; a passage leading from said port through the piston to the back thereof, whereby driving air may be admitted through the piston wall as well as through the cylinder enlargement; a second air inlet port in the cylinder wall; a passage in the cylinder wall leading to the 30 outside thereof; a second port in the piston wall leading to the longitudinal passage of the piston wall, the last mentioned ports of the piston and cylinder being positioned to come into co-operation on the return stroke 35 of the piston after the previously mentioned ports of the piston and cylinder; an exhaust port in the cylinder; and a passage in the cylinder wall forming a communication between said port and an exhaust outlet, one of 40 the ports in the piston wall being adapted to register with the said exhaust port at the end of the forward stroke of the piston.

7. A sound producing device comprising a cylinder having sound producing orifices 45 in its wall; a hollow piston adapted to reciprocate in said cylinder, open at one end and having sound producing orifices in its wall adapted to be brought into alinement with the orifices in the cylinder by the reciprocation of the piston; a chamber in the device for the sound-producing air supply; an enlarged head at the end of the piston remote from its open end; an enlargement of the cylinder in which the piston head reciprocates; an air inlet and an air outlet in said 55 enlargement; ports in the piston head and the wall of the cylinder enlargement controlling the admission and exhaust of the piston driving air; and supplemental ports 60 and passages in the stationary and movable ports for admitting air from the sound producing air supply of the apparatus to the space behind the piston at or about the end of the return stroke.

8. A sound producing device comprising

a cylinder having sound producing orifices in its wall; a hollow piston adapted to reciprocate in said cylinder, open at one end and having sound producing orifices in its wall adapted to be brought into alinement 70 with the orifices in the cylinder by the reciprocation of the piston; a chamber in the device for the sound-producing air supply; an enlarged head at the end of the piston remote from its open end; an enlargement of the cylinder in which the piston head reciprocates; an air inlet and an air outlet in said enlargement; ports in the piston head and the wall of the cylinder enlargement controlling the admission and exhaust of the 80 piston driving air; and supplemental ports and passages in the piston and cylinder walls for admitting air from the sound producing air supply of the apparatus to the space behind the piston at or about the end 85 of the return stroke.

9. A sound producing device comprising a cylinder having sound producing orifices in its wall; a hollow piston adapted to reciprocate in said cylinder, open at one end and having sound producing orifices in its wall adapted to be brought into alinement 90 with the orifices in the cylinder by the reciprocation of the piston; a chamber in the device for the sound-producing air supply; an enlarged head at the end of the piston remote from its open end; an enlargement of the cylinder in which the piston head reciprocates; an air inlet and an air outlet in said 95 enlargement; ports in the piston head and the wall of the cylinder enlargement controlling the admission and exhaust of the piston driving air; supplemental ports and passages in the stationary and movable ports for admitting air from the sound producing air supply of the apparatus to the space behind the piston at or about the end 100 of the return stroke; and supplemental ports and passages in the piston and cylinder walls for admitting supplemental driving air to the space behind the piston at the same time that the ports of the piston head and cylinder enlargement are admitting driving air thereto.

10. A sound producing device comprising a cylinder having sound producing orifices in its wall; a hollow piston adapted to reciprocate in said cylinder, open at one end and having sound producing orifices in its wall adapted to be brought into alinement 115 with the orifices in the cylinder by the reciprocation of the piston; a chamber in the device for the sound-producing air supply; an enlarged head at the end of the piston remote from its open end; an enlargement of the cylinder in which the piston head reciprocates; an air inlet and an air outlet in said 120 enlargement; ports in the piston head and the wall of the cylinder enlargement controlling the admission and exhaust of the piston driving air; and supplemental ports and passages in the stationary and movable ports for admitting air from the sound producing air supply of the apparatus to the space behind the piston at or about the end 125 of the return stroke.

5 piston driving air; supplemental ports and
10 passages in the stationary and movable ports
for admitting air from the sound producing
air supply of the apparatus to the space be-
hind the piston at or about the end of the
15 return stroke; and supplemental exhaust
ports and passages in the piston and cylin-
der walls adapted to exhaust air from be-
hind the piston at or about the same time
20 that exhaust is taking place through the
ports of the piston head and cylinder en-
largement.

25 11. A sound producing device comprising
a cylinder having sound producing orifices
in its wall; a hollow piston adapted to re-
ciprocate in said cylinder, open at one end
30 and having sound producing orifices in its
wall adapted to be brought into alignment
with the orifices in the cylinder by the re-
ciprocation of the piston; means for admit-
ting and exhausting piston driving air from
35 the cylinder; means for admitting sound-
producing air to the exterior of the part of
the cylinder provided with the sound pro-
ducing orifices; and means, controlled by the
piston for admitting sound producing air
40 behind the piston at or about the end of its
stroke in one direction.
